(57) **CLAIM**

The ornamental design for an air flow reducer disk, as shown and described.

DESCRIPTION

This application is related to pending Utility Application Ser. No. 09/660,569 filed on Sep. 12, 2003 by the same co-inventors, Linn et al.

FIG. 1 is a front perspective view of an airflow reducer disk showing my new design.

FIG. 2 is a front elevational view thereof.

FIG. 3 is a right side elevational view thereof.

FIG. 4 is rear elevational view thereof.

FIG. 5 is a left side elevational view thereof.

FIG. 6 is a top plan view thereof; and,

FIG. 7 is a bottom plan view thereof.
